UNITED STATES PATENT OFFICE

JACOB COLITZ, OF CHICAGO, ILLINOIS

CONDUIT RECEPTACLE

Application filed January 21, 1930. Serial No. 422,380.

My invention relates to conduits employed for electric wiring in buildings, and more particularly to the receptacles employed terminally of such conduits to adapt them for 5 an outlet unit, and my main object is to provide a novel arrangement in connection with the assembly of the receptacle with the conduits and the outlet unit whereby to do away with threading, locking means or other complicated parts for fastening the conduits to 10 the outlet unit.

A further object of the invention is to design the receptacles in units adapted for conduits singly or in pairs, as the case may be.

A still further object of the invention is to provide a basic support for the conduit receptacles with means for quickly and firmly attaching the latter whereby to hold the conduit in place.

Another object of the invention is to design the basic receptacle support with means for readily securing the same to the outlet unit.

25 An additional object of the invention is to provide intermediate means whereby to adapt a receptacle to an outlet opening of greater dimensions than ordinarily suitable for the receptacle.

30 A final but nevertheless important object of the invention is to design the novel assembly on lines of simplicity, economy and for ease of handling.

With the above objects in view and any
35 others that may suggest themselves from the
specification and claims to follow, a better
understanding of the invention may be had
by reference to the accompanying drawings,
in which—

40 Figure 1 is an elevation showing a terminal grouping of conduits as secured by the novel receptacle means;

Fig. 2 is an enlarged elevation of the installation, partly in section;

45 Fig. 3 is a plan view;

Fig. 4 is a section on the line 4—4 of Figure 3;

Fig. 5 is a section on the line 5—5 of Figure 4;

Fig. 6 is a perspective view of a single 50 receptacle; and

Fig. 7 is an elevation, partly in section of an assembly wherein the novel adapting means is interposed.

In the art of cement ceiling construction 55
in modern buildings, it is necessary that the outlet plate for electric wiring leads through the masonry be placed before the concrete is poured. The wiring is enclosed in conduits which extend horizontally between the ceiling and the floor above, and take bends at the site of the outlet plate and in the direction of the latter, then being secured to the outlet plate. The ceiling form for the concrete is composed of improvised layers 60
of boards, and it is to one of these that the outlet plate is nailed to hold its place. As shown in Figures 2 and 3, a plate of this kind is circular and cup shaped, the plate 10 having a downward ring flange 10a which rests on the form board (not shown). When the conduits 11 have been properly joined to the outlet plate 10, the concrete is poured as indicated at 12 to embed the entire assembly 65
above the form boards, so that when the latter are removed, the inside of the outlet 70
plate is exposed. The plate 10 is provided with a flange 10a which rests on the form board (not shown). When the conduits 11 have been properly joined to the outlet plate 10, the concrete is poured as indicated at 12 to embed the entire assembly 75
above the form boards, so that when the latter are removed, the inside of the outlet

latter are removed, the inside of the outlet plate will appear in the ceiling. In order that I may avoid the use of all threads and other accessory fastening means for the conduits, I have designed sheet metal casings 80 13 for the same, extending the sides thereof with opposed flanges 13a, perforated in registration as indicated at 13b and seen more clearly in Figure 6 to constitute the casings 85 as clamps when a bolt 14 and nut 15 are used to draw the casing flanges together. The casings flare slightly toward the top for facility in inserting the conduits. To guard against the withdrawal of any conduits from the casings due to vibration and also to establish 90

lish a firm electrical contact between the parts, I indent the casing as indicated at 13c to present downward spurs 13d on the inside, which dig into the relatively softer metal of 5 the conduit as the casing is clamped, locking the conduit against retraction. The casings are of a tubular nature and open at both ends, and near the lower end each is annularly indented as indicated at 13e to present 10 an internal bead which stops the advance of the conduit 11 as the latter is inserted, providing a support for the end of the conduit until the clamping of the same is effected. While the casing is open where the flanges 15 extend, it is in full and rigid form below the wings. With the conduit clamped as described, it is necessary that means be furnished to secure the clamped conduit to the outlet plate 10. I provide such means in the 20 form of a block 16 of prism or similar shape, and which is adapted to rest upon the outlet plate. As indicated in Figure 4, the block is longitudinally drilled with a horizontal bore 16a through which the bolt 14 is passed 25 from one end to receive the nut 15 at the other end. The bolt receives a washer 17 next to the head. While the block 16 may form a support for but a single conduit receptacle 13 of the type shown in Figure 6, it is 30 more probable that a plurality of receptacles will be required owing to the prevalent use of one outlet plate for more than one conduit. Thus, the receptacle may be extended laterally in dual or twin formation, as indicated 35 clearly in Figure 3, with the sheet metal formed from one piece and its ends spaced as shown. The metal flange is placed against the end of the block 16 and, of course, made with the aperture 13b as previously mentioned; but the ends denoting the outer flange may be notched as indicated at 13bb in Figure 2 to provide clearance for the bolt shank. Thus, with a dual receptacle unit at one end of the block 16 and a like one at the 45 other end thereof, accommodation is had for the disposal of four conduits, yet, when less than this number of conduits are had, but one single or dual receptacle unit is necessary. As noted, the washer 17 and the nut 15 are elongated vertically (see Figure 4), so that they may be confined between the receptacles and therefore prevented from turning as the bolt 14 is adjusted, saving the need of a wrench or special attention in this 50 respect; also the longation of the washer and nut cause the same to secure the outer flanges of the casings along a greater area.

The standard outlet plate is made with four large holes 10b corresponding in size and position with the conduits of Figure 3; with a central opening 10c; and with smaller apertures 10d diametrically arranged opposite the opening 10c. Also, beyond the apertures 10d are apertures 10e, but I make no use of the 55 latter apertures. Relative to the latter aper-

tures, I extend the bottom of the block 16 laterally with tongues 16b which are perforated at 16c. Further, I extend the block 16 downwardly with a neck portion 16d, a collar 16e, and a threaded nipple 16f. The latter is of a size to receive the lamp or other fixture designed to be hung from the outlet plate, and the collar 16 is of a dimension to easily pass through the opening 10c in the outlet plate as it is lowered therethrough to seat the block on the plate. However, I prefer to peripherally thread the collar for facility of insertion in instances where the opening 10c is smaller or has an internal burr or obstruction. The collar is fully eccentric relative to the neck portion 16d and the nipple 16f, so that when the block is shifted in the direction of the greater prominence of the collar, the latter will hook under the stock of the plate adjoining the opening 10c as clearly shown in Figure 2 and therefore lock the block from being again raised. This provides a connection between the block and the outlet plate which is integral with the block yet positive and without the necessity of any extra parts or appliances which may fit improperly or get out of order. In order that the locked condition of the block may be maintained, I apply a screw 18 downward through the aperture 16c of that block tongue 16b which is remote from the collar 16e. The aperture in the tongue is so placed that the screw will enter the outlet plate 10 along the outward edge of the corresponding aperture 10d with some friction, so that as the screw 18 is advanced the neck portion 16 of the block is forced in the engaging direction of the collar 16e whereby to bear firmly against the stock of the outlet plate and oppose influences to separate or turn the block. However, should it be necessary to turn the block for the adjustment of the collar 16e for any other purpose, I cut the top of the block with a transverse groove 16g to receive a screw driver or similar tool by means of which the block may be turned in case the collar 16e must be screwed through the plate opening. With the block secured as previously described, it is ready to receive the pouring of concrete which permanently fixes it in the position to which it has been set.

It will be noted in Figure 2 that the receptacles 13 are as units at a remote site from the central securing area of the block 16, and that each of them passes down through the corresponding opening 10b in a size suitable for such opening. In some cases, however, a particular opening may be much larger than a given conduit receptacle, in which case an adapter must be provided to fill the annular gap so occasioned. In Figure 7 I show such an adapter in the form of a short nut 19 which is amply large to cover the special opening and is internally tapped to be run on to the threaded end 13e of the conduit. The nut 19 has a short tubular reduction 19a externally 130

threaded as the collar 16e—and for the same purpose—and passing down through the opening in the plate, the end of this reduction being smoothly finished or rounded to present 5 no sharp or rough edges to the wire led through the same. The upper end of the nut 19 presents a ledge upon which the receptacle 13 is rested as shown. The conduit is thus definitely located relative to the larger plate 10 opening, and is held down by the receptacle in the same manner as previously described.

It will be seen that the novel receptacle installation provides an efficient intermediary between the conduits and the outlet plate. 15 With the conduits and outlet plate standard as to dimensions, the novel receptacle may be made by machine means to fit as installed, so that the assembly may be effected easily and rapidly. No delicate parts are involved to 20 get out of order or become lost; and the parts involved are of a simple and rugged nature, so as to be handled by the average mechanic without suffering injury or danger. The method of applying and installing the receptacle assembly is of a nature to become familiar to the mechanic after a few trials, so that further installations may be made rapidly and without special effort. Finally, the material and manufacturing methods 25 entering into the construction of the novel receptacle are such as to make rapid and economical manufacture of the product easily possible.

I claim:

35 1. An intermediary between the end portion of a conduit and the perforated outlet plate therefor, comprising a block applied medially to the upper surface of the plate, a conduit receptacle comprising a jacket 40 adapted to receive an end portion of the conduit, said jacket having perforated wings extended in opposed relation from the sides thereof, and securing means applied to the wings and the block to contract the jacket 45 upon the conduit and secure the jacket to the block.

2. An intermediary between the end portion of a conduit and the perforated outlet plate therefor, comprising a block applied medially to the upper surface of the plate, a conduit receptacle comprising a jacket 50 adapted to receive an end portion of the conduit, said jacket having perforated wings extended in opposed relation from the sides thereof, and a bolt directed through the wing 55 perforations into the block to contract the jacket upon the conduit and secure the jacket to the block.

3. A dual conduit receptacle comprising a 60 support, a jacket adjacent each end of the latter and adapted to each receive an end portion of a conduit, opposed and perforated wings extended from the jackets opposite the respective ends thereof, a bolt applied by way 65 of the perforations in one set of wings and

through the support to penetrate the other set of wings, and a nut applied to the bolt outside the latter.

4. The structure of claim 3, said jackets and wings being elongated in conformity with the 70 conduits, and said nut being made oblong to correspond, and a washer inwardly of the bolt head, the washer also being oblong in the longitudinal direction of the wings to which it is applied.

5. An intermediary between the end portions of conduits and the perforated outlet plate therefor, comprising a block applied medially to the upper surface of the plate, and 75 conduit receptacles carried by the block, said receptacles being positioned to register with the perforations in the plate.

6. An intermediary between the end portions of conduits and the perforated outlet 80 plate therefor, comprising a block applied medially of the plate, and conduit receptacles carried by the block, said receptacles being positioned to register with the perforations in the plate, said receptacles also being extended to pass through the plate.

7. An intermediary between the end portions of conduits and the perforated outlet plate therefor, comprising a block applied medially of the plate, and conduit receptacles carried by the block, said receptacles being 85 positioned to register with the perforations in the plate, and a nipple suitable as a fixture support extended from the block through a perforation in the plate.

8. An intermediary between the end portions of conduits and the perforated outlet 90 plate therefor, comprising a block applied medially of the plate, and conduit receptacles carried by the block, said receptacles being positioned to register with the perforations in the plate, and means to lock the block 95 against separation from the plate.

9. An intermediary between the end portions of conduits and the perforated outlet plate therefor, comprising a block applied 100 medially of the plate, conduit receptacles carried by the block, said receptacles being positioned to register with the perforations in the plate, a neck depending from the block through a plate perforation, and a laterally-extended enlargement carried by the neck and adapted to engage the under side of the plate adjacent to the perforation by a corresponding movement of the block whereby to 105 lock the block to the plate.

10. The structure of claim 9, said enlargement being a peripherally-threaded eccentric of a diameter passable through the plate perforation.

11. The structure of claim 9, a base extension of the block opposite the plate, and fastening means directed from said extension into the plate, said fastening means being effective when the block is in a position with its enlargement engaged as specified.

12. The structure of claim 9, a base extension of the block opposite the plate, and a screw directed from said extension into a perforation of the plate, said screw exercising a wedging effort against the outer wall of its perforation when the block is in a position with its enlargement engaged as specified with the effect of urging the block in the engaging direction of the enlargement.
13. The structure of claim 9, said enlargement being circular and peripherally threaded, and said block being recessed for the application of a tool to turn the same.

In testimony whereof I affix my signature.
15 JACOB COLITZ.
